UNITED STATES PATENT OFFICE.

WALTER E. AMBERG, OF CHICAGO, ILLINOIS, ASSIGNOR TO AMBERG STEEL COMPANY,
OF CHICAGO, ILLINOIS, A CORPORATION OF ILLINOIS.

NUT-MAKING PROCESS.

1,314,036.

Specification of Letters Patent. Patented Aug. 26, 1919.

Application filed February 1, 1918. Serial No. 214,869.

To all whom it may concern:

Be it known that I, WALTER E. AMBERG, a citizen of the United States, and a resident of Chicago, Cook county, Illinois, have 5 invented certain new and useful Improvements in Nut-Making Processes, of which the following is a specification.

My invention has to do with the production in large quantities of metal nuts, and 10 like articles of manufacture. Its object is to save metal; and to expedite the production. A further and special object is to provide for the continuous production of nuts and the like, in a wholly automatic way and 15 without waste, from rod stock which is readily obtainable in the market. A further object of the invention is to improve the quality and finish of such articles.

My invention comprises a novel process 20 and mechanism whereby these objects are attained; and will be readily understood on reference to the accompanying drawing, in which: Figure 1 illustrates the direct working parts which I use in carrying out my 25 novel process, and which themselves constitute a part of the invention; Figs. 2 to 7, inclusive, are like illustrations and depict the successive operations up to the discharge or 30 ejection of the finished article; and Fig. 8 depicts several, but not all, of the articles which may be produced by the means and in 35 the manner herein specified.

In Fig. 1 of the drawing, 1 represents a heating muffle or furnace. This is stationary. 2 represents a stationary shield opposite the mouth, 3, of the furnace; 4 represents a reciprocating rod propeller or clutch, of which 5 is the clutch part, the latter being a split cone. 5 represents a reciprocating 40 die-block, which contains the die-cavity, 7, and a central bore, 9. The part, 8, represents a metal rod, which emerges hot from the furnace and passes through the shield, 2, the clutch, 5, and through the bore, 9, in the die-block, 6. The bore, 9, preferably is 45 slightly larger than the rod, 8, to obviate any difficulty with irregularities in the latter. 10 represents a reciprocating die-block, which contains a bore, 11, which is in alignment with the bore, 9, of the block, 6, and

which preferably is of the same diameter. In the bore, 11, is a reciprocating plunger, 12, of which, 12', is the shank.

The parts above described appear also in each of Figs. 5 to 7, inclusive, but in the different relation which they occupy in different stages or steps of the process. The several dotted direction lines that connect the several figures are intended to facilitate the reading of the drawing with respect to 60 the movements which take place. In Fig. 1 the parts appear as at the moment of starting the cycle of operations represented by Figs. 2 to 7.

The shape of the article produced depends upon the shape of the die-cavity, 7. Obviously, this cavity may be a simple circular cavity, or may be polygonal or may be a more complex cavity, according to the shape and dimensions of the article to be 70 produced. Thus, as indicated in Fig. 8, articles of various shapes may be produced by changing the configuration of the die opening within and between the die-block, or members 6 and 10. 75

In making such articles, I use metal rods; passing them through the heating furnace, 1, and preferably welding the end of one rod to that of the next, so that the process may proceed continuously, and without interruption; and also to avoid a minor waste which would otherwise be suffered through the leaving of short ends of the rods to be cared for. However, the word "continuous," as 80 herein used, relates to the operations upon 85 any single rod, however short or long it may be.

At the start of the cycle, the rod will be found in the position depicted in Fig. 1, with the parts, 4, 6, 10 and 12, in the positions there indicated. As shown in Fig. 1, the propelling member or clutch is in retracted position ready to move the stock or rod forward. It will be understood that the rod, 8, preferably is hot; that is, at a temperature which will permit the upsetting of the end of the rod without cracking or fracturing the metal. 90

The step which begins the cycle, as shown in Fig. 2, consists in pushing the clutch, 4, 95 100

forward against the then stationary block, 6. This, obviously, drives the rod forward through the die bore, 9, and the cavity, 7. This movement of the rod (by the clutch block) is adjusted to project just so much of the end, A, of the rod, 8, as will yield a sufficient body of metal to substantially fill the cavity, 7. I prefer that the block, 10, and plunger, 11, shall be adjusted so that the 10 end of the rod may be received in the plunger cavity or bore, 11, as shown in Fig. 2.

Having thus provided sufficient metal to form the article, and while holding the members, 4 and 6, stationary, I next drive 15 the block, 10, and plunger, 12 toward and against the block 6. This movement upsets the portion, A, of the rod, 8, and thereby at least partially fills the cavity, 7; thus forming the body of metal, B, as illustrated in 20 Fig. 3.

Having substantially filled the cavity, 7, with metal, B, I next drive the plunger, 12, inward, as shown in Fig. 4, to displace from the central portion of the body enough metal 25 to fill all of the corners of the cavity, 7, thus producing the externally completed metal body, C.

Attention is here directed to the fact that in the upsetting operations, (Figs. 2, 3, and 30 4) the clutch member takes the thrust of the die block, 6; also to the fact that in the upsetting operation the bore, 9, of the block, 6, is completely filled by the upsetting of the metal therein. This upsetting is done 35 against the end of the clutch part, 5, which contains the smaller bore. In this manner I avoid forming a swell or enlargement between the parts 5 and 6, which if formed would prevent the further driving in of the 40 rod. The consumption of metal is made clear by the sectioned parts, 13, of the rod. An accurate gage may also be noted in the presence of the small shoulder, 14, which is formed on the rod at the point where the 45 clutch, 5, and the block, 6, abut.

Having completely formed the body of the nut or other article, in the manner depicted in Fig. 5, I lock the plunger, 12, in position; and then force the blocks, 6 and 10, 50 forward together, over the end of the plunger. In this manner I successfully strip or shear the up-setted metal off the central portion of the stock, to-wit, from the portion which initially formed the central part of 55 the body of metal, C. In effect I punch a hole in the body, C, and at the same time leave the punched-out portion or plug still attached to the stock, 8. In brief, I thereby complete the nut without wasting the plug 60 which is usually punched from the center of a nut; accomplishing this by the simple act of stripping the nut off of the parent stock and thus leaving the plug as an integral part of the parent stock.

The article having been completed within 65 the compass or confinement of the die-blocks, 6 and 10, I next retract the die-block, 6, and also retract the plunger, 12, as shown in Fig. 7, thereby freeing and discharging or ejecting the completed nut and at the same 70 time restoring the parts, 6, 10, and 12, to the starting positions, first shown in Fig. 1. In Fig. 7 the completed nut, E, is shown in two positions: first as at the instant of the retraction of the parts 6 and 12; and, second, 75 as the nut appears when dropping from that position.

A complete cycle of operation, as above described, occurs within a fraction of a minute. As will be apparent to those skilled 80 in the art, no part of the operation requires that either the stock or the die blocks shall move slowly. The capacity of the machine is great. It is wholly automatic in operation, once the end of a rod is caught in the 85 clutch, 5, and power supplied to move the several members described.

As every article is subjected to compression within the restraining die, and as even the central opening in the article is formed 90 while the metal is under compression, the article produced is of superior quality both as to the state of the metal composing it and the character and finish of its surfaces.

By way of contrast, it may be stated that 95 in the manufacture of square nuts by ordinary methods, there is a waste of metal amounting to about thirty per cent.; and in the usual making of hexagonal nuts, there is a loss of approximately sixty per cent. By 100 my process and mechanism, I accomplish the manufacture of all such articles without any waste whatever, and at the same time produce the articles much more rapidly.

I have not herein attempted to illustrate 105 means for imparting movement to the members, 4, 5, 6, 10 and 12. These parts may be moved by means of several mechanisms which will suggest themselves to a competent mechanic.

Various modifications of my invention 110 will suggest themselves to those skilled in the art, and it is possible to modify the order of the steps described. Therefore I do not limit the invention to the precise preferred order and construction herein described, except as prescribed by the hereunto appended claims.

Having thus described my invention, I claim as new and desire to secure by Letters 120 Patent:—

1. The improvement in the art of making metal nuts, which consists in advancing the stock, upsetting the end thereof, and thereafter advancing the upset end to strip it off 125 the stock.

2. The improvement in the art of making metal nuts, which consists in upsetting and

shaping an end of the stock and thereafter advancing the upset end thereof to form the bore of the nut and to strip it off the stock.

3. The improvement in the art of making metal nuts, which consists in advancing a metal rod and upsetting the end thereof to form the body of the nut, and then stripping off the nut by moving the nut portion longi-

tudinally of the rod, leaving as the extreme end of the rod the portion of metal which 10 previously formed a portion of the upset end thereof.

In testimony whereof, I have hereunto set my hand this 25th day of January, 1918.

WALTER E. AMBERG.
